UNITED STATES PATENT OFFICE.

ELI A. RUSSELL, OF CHICAGO, ILLINOIS.

COIN BANK.

Application filed February 20, 1925. Serial No. 10,445.

My invention relates to coin banks.

The object of the invention is to provide a simple, practical and effective construction of coin bank, and particularly to provide a simple, inexpensive and quickly operated locking device by which the bank may be normally locked to prevent loss or withdrawal of coins and by which the bank may be opened by an authorized person to permit deposit or use of the coins.

In the accompanying drawings Fig. 1 is a side elevation of a coin bank embodying my invention;

Fig. 2 is a cross section taken on line 2—2 in Fig. 1;

Fig. 3 is a cross section taken on line 3—3 in Fig. 2;

Fig. 4 is a cross section taken on line 4—4 in Fig. 2; and

Fig. 5 is a view of a portion of the bank as shown in Fig. 4 in process of being unlocked.

In the drawings I show a bank consisting of a bottom or body portion 1 and a top or cover 2 fitting on the body portion 1. The bank is preferably a small flat device suitable to be carried in the pocket and consequently the body 1 is a low cylindrical structure and top 2 is a flat circular or disk-like member fitting thereon. The body 1 has a coin chamber or receptacle 3, into which the coins are deposited, a coin slot 4 being shown for that purpose.

The top or cover 2 is detachably mounted on the body 1, and means are provided by which said cover is locked to the body 1 so as to retain the coins within the bank, said locking means also permitting the cover to be detached, to allow the removal of the coins either for use or for deposit in a banking institution or other authorized purpose as desired.

To such end the body 1 is provided with an annular flange 6, and the top 2 with a disk-like member 7 having an edge portion 8 adapted to rest on flange 6, said member 7 also having radially projecting prongs or teeth 8 and the flange 6 having cutaway portions or recesses 9 adapted to receive prongs 8. The projections 8 and recesses 9 are arranged to register with one another when the top is put in position on the base, and when this is done the prongs 8 will pass underneath flange 6 and by turning the top 2 slightly with reference to bottom 1, said top 2 will be held against outward move-

ment tending to separate it from bottom 1, and consequently open the bank. A rotative movement of parts 1 and 2 however bring the prongs 8 and recesses 9 into register with one another, and so permit separation of parts 1 and 2 and the opening of the bank.

To prevent such rotative movement normally and retain the bank in a closed position, I provide a locking device comprising a spring clip 10 secured as by rivets 11 to cover member 7, said clip 10 having a prong 12. The body 1 is provided with a co-operating locking member 13 which is preferably made integral with annular flange 6. Said member or lug 13 is provided with a recess 14 having a side orifice 15 through which prong 12 may pass, and also has an abutment 16 by which the side of said prong 12 may be engaged, as shown in Fig. 4. When prong 12 is so located in recess 14 and engaged by abutment 16 the cover 2 will be held or locked against rotation relatively to body 1, and consequently the bank will be locked in a closed condition.

To unlock the bank and permit it to be opened a key 17 is provided and this key is adapted to enter a key hole 18 in body 1 and also to enter a key hole 19 in depending flange or lug 13. Key 17 has a side projection 20 adapted and arranged when the key is turned to contact with the upper edge of prong 12 and so depress said prong so as to disengage it from abutment 16, as shown in Fig. 5. Said key projection 20 also shifts prong 12 slightly to one side, that is to the left, referring to Figs. 4 and 5, so that when prong 12 is out of engagement with abutment 16 it is also out of position to return to locking position in recess 14, in fact resting on the point or end of abutment 16, as shown in Fig. 5. Thus the unlocking key 17 will not only cause prong 12 to be moved to unlocking position, but will also cause it to be held in such position, so that cover 2 may be turned with reference to body 1, this turning being to an extent to cause prongs 8 to register with recesses 9 and so permit the separation of the body 1 and cover 2. Thus the key after it performs its unlocking operation need not necessarily be held in unlocking position, but may be moved further along to some other position, or even removed from the key hole entirely, so that no matter what is done with key 17 after it is turned to perform the unlocking

operation, the spring prong 12 will be held in unlocked condition so as to permit relative rotative movement between parts 1 and 2 and the consequent unlocking and opening 5 of the bank. To relock the bank in closed condition cover 2 and body 1 are put together and prongs 8 caused to register with recesses 9 and then said parts 1 and 2 turned relatively to an extent to cause spring prong 10 12 to slide along inclined surface 23 of abutment 16 and over the top or point of said surface into recesses 14, so that prong 12 will settle in the upper portion of said recess and be again engaged by abutment 16 to 15 prevent relative rotation of parts 1 and 2.

It will be seen that the device is extremely simple, the locking arrangement having but a single spring clip and a cooperating socket or recess member, and also that locking and 20 unlocking may take place quickly and easily, and also that tampering or meddling with the locking device by unauthorized persons is very difficult, if not actually impossible.

It will be understood that changes and 25 modifications may be made without departing from the spirit of the invention.

What I claim is:

1. A coin bank having a locking device comprising cooperating locking members, 30 one of which is adapted to be moved to unlocking position by a key and also adapted when so actuated to be moved to a position for holding it in unlocking position, said member being adapted to be held in said 35 position by said cooperating member.

2. A coin bank having a locking device comprising interengaging locking members, one of which is adapted to be actuated by a 40 key so as to disengage it from the other, and means for holding the same out of engaging position, said means being provided by the other of said members.

3. A coin bank having locking means comprising a spring clip and a recess into which 45 said clip may pass and an abutment at the mouth of said recess, said clip being adapted to be held in said recess to effect a locking engagement, and also adapted to be lifted out of the same and to be moved to one side 50 by a key so as to rest on said abutment.

4. A coin bank having locking means comprising a spring clip and a recess into which 55 said clip may pass and an abutment at the

mouth of said recess, said clip being adapted to be held in said recess to effect a locking 55 engagement, and also adapted to be lifted out of the same and to be moved to one side by a key so as to rest on said abutment, said spring clip being mounted on one member of said bank and a recess being formed in a 60 lug on the other member of the bank, and said members being relatively rotatable and held against rotation by said locking means.

5. A coin bank comprising relatively rotatable cover and body members, whereof the top member is provided with a spring locking clip and the body member is provided with a lug having a recess to receive the end of said locking clip and also having an abutment to prevent movement of said 70 end out of said recess, said clip end being adapted to be actuated by a key so as to lift it out of said recess, and move it slightly to one side so that it will rest on said abutment, and prongs and recesses on said cover and 75 body members adapted to permit relative rotation between said members, said locking device being adapted to hold said members against relative rotation, and thus cause them to be locked together. 80

6. A coin bank comprising relatively rotatable cover and body members, whereof the top member is provided with a spring locking clip and the body member is provided with a lug having a recess to receive 85 the end of said locking clip and also having an abutment to prevent movement of said end out of said recess, said clip end being adapted to be actuated by a key so as to lift it out of said recess and move it slightly to 90 one side so that it will rest on said abutment, and prongs and recesses on said cover and body members adapted to permit relative rotation between said members, said locking device being adapted to hold said members 95 against relative rotation and thus cause them to be locked together, said body member being provided with an annular flange to support the top or cover and said lug being adapted to and extending downwardly from 100 the inner edge of said annular flange.

In witness whereof, I hereunto subscribe my name this 20th day of January, A. D. 1925.

ELI A. RUSSELL.
